CARTRIDGE TRANSFER TOOL

John R. Hull, Kansas City, Mo., assignor to Remington Arms Company, Inc., Bridgeport, Conn., a corporation of Delaware

Application September 10, 1953, Serial No. 379,353

1 Claim. (Cl. 86—47)

2

The present invention contemplates a tool adapted to be applied to the holder *d* of the clip to facilitate applying the clip to such a row of cartridges. The tool comprises a handle **10** embracing a tang or shank **11** which projects from one end of the handle. To cut-outs adjacent the projecting end of shank **11** are secured, by suitable means such as rivets **12**, two prongs **13** which extend outwardly from the end of the shank **11** and are so spaced and of such dimensions as to be received in the channels formed by the side walls *e* and lips *f* of the holder *d*. When the tool is thus applied to a clip, the end of holder *d* comes to rest against the end of the shank **11**, and upon grasping the handle **10** the clip can be advanced over a pre-arranged and supported row of cartridges with great facility.

The end of shank **11** comprises a projecting pad **14**, preferably of arcuate configuration, which is adapted to engage the tongue *c* of spring member *b*, which tongue as presented to the tool is in the plane of the back of said spring member. When cartridge receiving pressure is applied to the tool, the tongue *c* is thereby turned to a position at right angles to the length of the row of cartridges, thus enabling the tongue to retain cartridges in place in the clip.

The tool has been found to be most useful in the clipping of caliber .30 carbine cartridges, both greatly increasing the speed of this operation and eliminating minor injuries to personnel engaged in this operation.

What is claimed is:

30 A hand tool for loading a cartridge clip comprising a cartridge receiving track, a displaceable tongue at the end of said track and substantially in the plane thereof and a widened holder including side walls adjacent one end of said track and laterally spaced therefrom, said tool comprising a handle, parallel prongs extending from one end of said handle in spaced relation for entry in said widened holder between said side walls and said track of said cartridge clip, and a projecting pad formed on said handle between said prongs having a concave arcuate face whose axis of curvature is perpendicular to said prongs, said arcuate face being disposed to engage and displace said tongue from the plane of said track when a cartridge clip is thrust between said prongs.
